ROTARY ENGINE.

1,225,844.

Specification of Letters Patent.

Patented May 15, 1917.

Application filed June 12, 1916. Serial No. 103,271.

To all whom it may concern:

Be it known that I, AUGUST E. MUELLER, a citizen of Argentina, South America, and a resident of Chicago, in the county of Cook 5 and State of Illinois, have invented certain new and useful Improvements in Rotary Engines; and I do hereby declare that the following is a full, clear, and exact description thereof, reference being had to the accompanying drawings, and to the characters of reference marked thereon, which form a part 10 of this specification.

This invention relates to improvements in rotary engines and, as herein shown, is designed more specifically for use as a steam 15 or compressed air engine.

Among the objects of the invention is to simplify and improve rotary engines, and the invention consists in the arrangement 20 and combination of the parts shown in the drawings and described in the specification and is pointed out in the appended claims.

As shown in the drawings:—

Figure 1 is a side elevation of a rotary 25 engine embodying my invention.

Fig. 2 is a plan view thereof with the parts broken away.

Fig. 3 is a side elevation of the rotor and one-half of the stator or casing.

Fig. 4 is a vertical section on the line 4—4 of Fig. 1.

Fig. 5 is a side elevation of the rotor removed from the other parts.

Fig. 6 is a view similar to Fig. 3, showing 35 a modification.

Fig. 7 is a vertical section on the line 7—7 of Fig. 6.

First, referring to the construction shown in Figs. 1 to 5 inclusive, 10 designates the 40 stator or casing of the engine which is made of two like parts 11, 11 that are fastened together by bolts 12 or other suitable fastening means, a packing 13 being interposed between the faces of said casing parts to 45 provide a fluid-tight joint. 15 designates as a whole the rotor within said casing. It comprises a central annular portion 16 having a smooth periphery to fit and rotate within an annular recessed portion 17 of the 50 casing, and two annular series of oppositely directed blades 19, 19 which fit within annular steam chambers 20, 20 of the casing or stator. The said blades 19 preferably, and as herein shown, are triangular 55 in longitudinal section, being widest at their

bases and having flat faces 21 and oppositely disposed oblique faces 22. Preferably, and as herein shown, the outer ends of said blades are convexly curved to fit the concave ends 23 of the chambers 20, while 60 the radially inner and outer sides thereof are parallel to each other and to the axis of rotation of the rotor to conform to the concentric inner and outer walls of the steam chambers. 25 designates a shaft 65 which extends through suitable bearings 26, 26 in the casing and through an opening in the stator 15 and is keyed or otherwise suitably secured to the rotor. Between said bearings 26 and the chambers 20 the casing 70 parts are arranged with flat inner faces 28 to fit the flat inner circular face 29 of the stator radially within the blades 19. The said blades are shaped and dimensioned to fill the steam chambers 20. In order to provide substantially fluid-tight joints between the blades and the walls of the chambers 20. U-shaped packing members 31 may be employed, adapted to fit within grooves formed 75 in the inner and outer and end faces of said blades. The said packing members 31 are made of material possessing some resiliency so that the arms thereof tend to spread outwardly for contact with the radially inner and outer walls of the chambers. In order 80 to press the packing members 31 against the lateral concave end walls 23 of the chambers 20, I may provide springs 33 which are inserted in suitable sockets in the rotor and bear against the ends of the U-shaped packing members in the manner most clearly 85 shown in Fig. 4.

Each side of the casing or stator is provided, at its bottom as herein shown, with an exhaust port 40, and said ports may be 90 connected by pipes 41, 41 to a common exhaust pipe 42. Each side of the stator casing is also provided with two inlet ports 43, 44, through one of which steam is admitted to drive the rotor forwardly and 95 through the other of which steam is admitted to reverse the engine or drive the rotor rearwardly. Said ports 43 may be connected by pipes 45 to a common supply pipe 46 equipped with a valve 47. The ports 44 may 100 be likewise connected by pipes 48 to a common valved feed pipe 49. The said casing parts are also provided with supplemental inlet ports 50 and supplemental outlet ports 51, the former connected by branches 52 110

to a valved supply pipe 53, and the latter connected by branches 54 to an open exhaust pipe 55.

The said inlet ports are disposed tangentially to the path of rotation of the circular series of blades so that the motive fluid, entering the cylinder or casing through said ports, strikes the blades at an effective angle to produce rotation of the rotor. The parts are so arranged that the motive fluid entering through the inlet ports 43 and 51 strikes the flat faces 21 of the blades to drive the rotor in a forward direction, while the motive fluid which passes into the casing through the reverse ports 44 strikes the oblique faces 22 of the blades. The blades are made wide at their bases to produce the triangular shape shown in order to partially fill the steam chambers and thereby economize in the use of the motive fluid, and also to strengthen the blades.

The provision of inlet and exhaust ports at both sides of the casing is advantageous, inasmuch as the pressure of the motive fluid is equalized on both sides of the rotor, so that thereby side thrust of the rotor against its bearings in the casing and consequent retarding friction is avoided.

When operating the engine to produce moderate power and when driving it in a forward direction, the motive fluid is delivered to the cylinder or casing through the inlet ports 43 and is exhausted therefrom through the outlet ports 40. If greater power be required the valve of the pipe 53 is opened to admit the motive fluid through the inlet ports 51 on the side of the axis of the rotor opposite to the other inlet ports, and the motive fluid is exhausted through the outlet ports 50. With this construction power is applied to the rotor on opposite sides of its turning axis and thereby increases the power output of the engine.

In order to prevent the rotor from being driven backwardly in the event that the load tends to drive the motor, as, for instance, when a vehicle driven by the motor is climbing a hill and the power of the engine momentarily fails to drive the vehicle, I may provide a brake device such as is shown in Figs. 3 and 4 and which is made as follows: The walls of the recesses 17 of the casing or cylinder are provided with notches 60 in which are seated roller elements 61. Said notches 60 have oblique or inclined walls which merge at one end into the inner surfaces of the recesses. The other ends of the notches are enlarged beyond the diameter of the roller elements 61. Springs 62 tend to press the roller elements toward the inclined walls of the notches. They are adapted to be held away from said inclined walls, however, against

the action of the springs 62, by means of an eccentric 63 which is rotatively mounted in the casing wall and is adapted to bear against rods 64 which in turn bear against said roller elements. The construction and arrangement is such that when the eccentric, actuated by a handle 66, is swung to one limit of its movement, it acts, through one of the rods 64, to force the corresponding roller element into the larger part of the notch 60 against the action of one of the springs, while permitting the other spring 62 to force the other roller element against the inclined wall of the notch. In the adjustment shown in Fig. 3 the rotor is free to rotate in an anti-clockwise direction, but will be locked from rotation in the opposite direction by the left-hand roller element 61. The reverse adjustment of said eccentric 63 will produce a reversal of the conditions of rotation.

In the construction heretofore described, it has been assumed that the power is taken from the extended end of the shaft 25 to drive a single machine or machine element. In the use of the engine to drive two machine elements at differential speeds, as, for instance, when applied to the axle of a vehicle to drive the wheels thereof, which, due to steering movements, are required to be differentially driven, I may embody between engine case or cylinder and its driving axle a differential driving gear mechanism, such as is shown in Figs. 6 and 7.

The engine shown in said latter figures is in other respects the same as the construction already described with the exception of its connection to the driving shaft. In the latter construction the driving shaft is made of two parts or members 70, 70, on the inner ends of which are mounted beveled gear wheels 71, 71 which mesh with idler conical pinions 72 that are rotatively mounted in any suitable manner on shafts 73 carried by the rotor frame or body. With this construction the shafts 70 are driven at equal speeds when the vehicle is traveling in a direct line and are driven at differential speeds when the vehicle is rounding a curve.

It will be understood that the marginal portion of the body 16 of the rotor fits the annular and side walls 17, 17', respectively, sufficiently close, and that the lateral faces of the central portion of said body fits sufficiently close upon the flat faces 28 of the casing members so as to provide a practically effective barrier against the passage of steam or other motive fluid from one side of the engine to the other. It will also be understood that suitable packing may be employed between said bearing portions if found necessary or desirable.

I claim as my invention:—

1. A rotary engine comprising a casing

- provided with a central unobstructed annular space and with laterally opposed steam chambers; a rotor comprising a disk-like body in said central space and provided with two annular series of oppositely directed blades which extend into said steam chambers; inlet ports arranged to admit motive fluid simultaneously to said chambers at both sides of the rotor for impact with the blades and to balance pressure on opposite sides of the rotor, and exhaust ports communicating also with said steam chambers. 5
2. A rotary engine comprising a casing formed with a central unobstructed space to receive the body of a rotor and provided with laterally opposed annular steam chambers; a rotor rotatively mounted in said central space by means which divides or 10 separates said steam chambers and provided with two annular series of oppositely directed blades which extend into said steam chambers, with means to afford fluid-tight joints between the edges of the blades and 15 the walls of the steam chambers; inlet ports opening into said steam chambers at both sides of the rotor, and open exhaust ports leading from said steam chambers. 20
3. A rotary engine comprising a casing formed with a central unobstructed space to receive the body of a rotor and provided with lateral annular steam chambers; a rotor rotatively mounted in said central space by means which divides or separates said 25 steam chambers and provided with two annular series of oppositely directed blades which extend into said steam chambers, with means to afford fluid-tight joints between the edges of the blades and the walls 30 of the steam chambers; inlet ports leading into said steam chambers at both sides of the rotor and disposed in a plane at one side of the axis of rotation thereof; other inlet ports leading to said steam chamber 35 at both sides of the stator and disposed in planes at the other side of the axis of rotation of the rotor, and open exhaust ports in planes on opposite sides of said axis of rotation and leading from said steam 40 chambers. 45
4. A rotary engine comprising a casing formed with laterally separated annular steam chambers; a rotor therein to separate said steam chambers and provided 50 with two annular series of oppositely directed blades and two sets of inlet ports leading to the steam chambers on respective opposite sides of the axis of rotation of the rotor, and outlet ports leading from 55 said steam chambers. 60
5. A rotary engine comprising a casing provided with laterally spaced steam chambers; a rotor in said casing constituting a fluid barrier between said steam chambers and provided with oppositely directed 65
- blades which extend into said steam chambers; inlet ports leading to the steam chambers on respective opposite sides of the axis of rotation thereof, and exhaust ports arranged between the inlet ports to serve as 70 a common exhaust for motive fluid admitted to said steam chambers through said inlet ports, whereby the engine may be driven in either of two opposite directions. 75
6. A rotary engine comprising a casing provided with laterally spaced steam chambers; a rotor in said casing constituting a fluid barrier between said steam chambers; inlet ports leading to the steam chambers on opposite sides of the axis of rotation thereof, with exhaust ports arranged between the inlet ports to serve as a common 80 exhaust for motive fluid admitted to said steam chambers through the inlet ports, whereby the engine may be driven in either of two opposite directions, and supplemental inlet and exhaust ports on the side of the axis of rotation of the rotor remote from 85 said main inlet and exhaust ports. 90
7. A rotary engine comprising a casing provided with an annular steam chamber; a rotor therein mounted for substantially fluid-tight joints with the casing and provided with laterally directed blades which extend into the steam chamber; means 95 affording fluid-tight joints between said blades and the walls of the steam chamber, and inlet and exhaust ports for said steam chambers. 100
8. A rotary engine comprising a casing provided with an annular steam chamber; a rotor therein mounted for substantially fluid-tight joints with the casing and provided with laterally directed blades which extend into the steam chamber; expanding 105 packing members carried by said blades and engaging the steam chamber walls with a packing fit, and inlet and exhaust ports for said steam chambers. 110
9. A rotary engine comprising a casing having an annular steam chamber; a rotor mounted in the casing and provided with laterally directed blades which extend into said annular steam chamber, said blades each having a straight face substantially parallel 115 to the axis of rotation of the rotor and an opposite oblique face, giving general triangular shape thereto, and inlet and exhaust ports for the steam chamber. 120
10. A rotary engine comprising a casing having an annular steam chamber; a rotor mounted in the casing and provided with laterally directed blades which extend into said annular steam chamber, said blades each having a straight face substantially parallel 125 to the axis of rotation of the rotor and an opposite oblique face, giving general triangular shape thereto; inlet and exhaust ports for the steam chamber, and expanding packing members carried by said blades for fluid- 130

tight joints with the walls of said steam chambers.

11. A rotary engine comprising a casing provided with an annular steam chamber; a 5 rotor therein mounted for substantially fluid-tight joints with the casing and provided with laterally directed blades which extend into the steam chamber; expanding 10 packing members carried by said blades and engaging the steam chamber walls with a packing fit; inlet and exhaust ports for said steam chambers at one side of the plane of the turning axis of the rotor, and supplemental inlet and exhaust ports for the steam 15 chambers at the other side of said axis.

12. A rotary engine comprising a casing having an annular steam chamber; a rotor mounted in the casing and provided with laterally directed blades which extend into 20 said annular steam chamber, said blades each having a straight face substantially parallel to the axis of rotation of the rotor, and an opposite oblique face giving general triangular shape thereto, and inlet and exhaust ports 25 for the steam chamber, said blades being grooved on their radially inner and outer sides and at their ends and packing members inserted in said grooves.

13. In a rotary engine, the combination 30 with a casing having a steam chamber, with inlet and outlet ports, of a rotor in said casing having blades which extend into said steam chamber, and expanding packing members carried by said blades for fluid-tight packing contact with the walls of said steam chamber.

14. A rotary engine comprising a casing having an annular steam chamber; a rotor mounted in the casing and provided with 40 laterally directed blades which extend into said annular steam chamber, said blades each having a straight face substantially parallel to the axis of rotation of the rotor, and an opposite oblique face giving general triangular shape thereto, and inlet and exhaust ports 45 for the steam chamber, said blades being grooved at their radially inner and outer sides and at their ends; U-shaped resilient packing members seated in said grooves and 50 springs acting on the arms of said packing members to press the same toward the end walls of the steam chambers.

15. In a rotary engine, a casing or cylinder provided with an annular steam chamber; a rotor therein provided with triangular shaped blades having straight faces par- 55

allel to the axis of rotation of the rotor and opposed oblique faces; an inlet port for the steam chamber arranged to direct motive fluid against the flat faces of the blades, and 60 an exhaust port leading from said steam chamber.

16. A rotary engine comprising a casing formed with an annular steam chamber; a 65 rotor therein provided with laterally directed blades which extend into the steam chamber, and inlet and outlet ports communicating with said steam chamber on opposite sides of the axis of rotation of the rotor, whereby the energy of the power medium 70 may be directed simultaneously against the blades of the rotor at opposite sides of said axis of rotation.

17. A rotary engine comprising a casing provided with an annular steam chamber 75 and with inlet and outlet ports; a rotor rotatively mounted therein and provided with laterally directed blades having thickened bases to limit the steam area of the steam chamber.

18. A rotary engine comprising a casing provided with a steam chamber; a centrally recessed rotor mounted therein and provided with blades which extend into said chamber; inlet and exhaust ports leading respectively 85 to and from said chamber; divided shafts having bearing in said casing, and a differential drive gear mechanism within the recess of the rotor for connecting said rotor to said divided shafts.

19. A rotary engine comprising a cylinder or casing; a recessed rotor therein; divided shaft members having bearing in the casing, and differential drive gear mechanism in the recess of the rotor and connecting said shafts 95 and rotor.

20. A rotary engine comprising a casing; a recessed rotor therein; inlet and exhaust ports leading, respectively, to and from the casing; divided shaft elements having bearing in the casing and provided within the casing with beveled gears, and idler beveled gears mounted in the recess of the rotor and meshing with the beveled gears of the divided shaft elements.

In witness whereof, I have hereunto set my hand at Chicago, Illinois, this 24th day of May, 1916.

AUGUST E. MUELLER.
